ATTORNEY.

UNITED STATES PATENT OFFICE.

HALSEY C. ABERN, OF CHICAGO, ILLINOIS.

CARBURETOR.

Application filed September 19, 1925. Serial No. 57,831.

My invention relates to a new and useful improvement in a carburetor and has for its object, the provision of a carburetor having means for producing a vacuum in the carburetor adapted for dispensing with the vacuum tank now customarily used with the oil supply systems of motor vehicles.

Another object of the invention is the provision in a carburetor having a plurality of fuel ports of means for closing one of said ports upon the flow of fuel through the other of said ports in sufficient quantities.

Another object of the invention is the provision in a carburetor of sealing means, adapted for sealing a portion of said carburetor from the remainder of the interior thereof, for permitting the producing of a vacuum in the carburetor for facilitating the flow of fuel into the carburetor from the fuel tank.

Another object of the invention is the provision in a carburetor of this class of a flexible compartment forming member having a vibratory wall, adapted for sealing one portion of the carburetor from the other, for producing a vacuum in the carburetor and adapted for automatically unsealing these compartments upon the flow of a sufficient amount of fuel into the carburetor for the purposes for which used.

Other objects will appear hereinafter.

The invention consists in the combination and arrangement of parts hereinafter described and claimed.

The invention will be best understood from a reference to the accompanying drawing which forms a part of this specification and in which,

40 The figure is a longitudinal vertical sectional view of the invention.

The invention, as shown in the drawing, comprises a casting adapted for forming an upper wall 7, having a flange 8 projecting downwardly therefrom and provided with a shoulder 9. A cylindrical sleeve 10 is adapted for engagement between the shoulder 9 and the flange 8, a gasket 11 being interposed between the inner surface 50 of the upper wall 7 and the upper edge of the sleeve 10. The lower wall of the casing is formed by a casting 12 having an upwardly extending flange 13 and a shoulder 14 and between the flange 13 and the shoulder 14, the lower edge of the cylindri-

cal sleeve 10 is adapted to engage. A suitable gasket 15 and a gasket 16 are in engagement with the upper surface of the wall 12. Projecting downwardly from the wall 7 is a hollow neck 17 formed concentrically with which, in the wall 7, is a socket 18 having a wall thereof threaded, adapted for receiving the threaded end of a pipe 19, which is provided with a head 20. The passage 21, which extends longitudinally of the pipe 19 is in communication by means of the passageways 22 with a chamber 23, formed in the bowl shaped member 24 from which projects the neck 25, said neck 25 having a passageway 26 formed therein to communicate with the chamber 23, a suitable screen 27 being positioned in the chamber 23 in embracing relation to the pipe 19, so as to thoroughly screen the fluid flowing from the passage 26 into the passage 21. A nipple 28 is threaded into the neck 25 and also threaded into a tapered nipple 29, with which suitable piping may be connected to deliver fluid into the chamber 23 from the fuel tank, which is used with the vehicle to which the carburetor is to be attached. Positioned in the carburetor, so as to form a chamber 30, is a cup-shaped member having side walls 31, the ends of which are angularly turned and positioned between the gaskets 15 and 16. The base 32 of the cup-shaped member is provided with an opening 33 to permit the passage of the pipe 19 therethrough. It will be noted that the opening 33 is of less diameter than the bore of the neck 17, so that the base 32 engages against the edge of the neck 17 when flexed upwardly into engagement therewith. It will be noted that there normally is a space between the edges of the neck 17 and the base 32.

After the cup-shaped member has been placed in position and the cylindrical sleeve 10 engaged between the flanges and the shoulders already noted, a threading of the pipe 17 into the bore 18 will serve to bind the base 12 into close engagement, so as to securely clamp the cup-shaped member in position, the threading of the pipe 19 also serving to retain the bowl-shaped member 24 in position. Mounted in the carburetor, above the cup-shaped member, is a float 34 which is hingedly connected to a lug 35 which depends from the upper wall 7. Attached to the other end of the float 34 is a

clip 36 which embraces a needle 37, said needle being projected into the passageway 38 formed in the upper wall of the casting, said passageway being vertically extended 5 and communicating with a horizontally directed passageway 39 formed in said casting, the passageway 39 communicating with the passage 40, which opens into the interior 41 of the pipe which is provided with the flange 10 42 for attachment to the intake manifold of the motor with which used. Threaded into the upper wall 7 is an adjustment screw 15 valve 43 which is provided with a passageway throughout the major portion of its length, said passageway being adapted for 20 communication through laterally extending openings with the passageway 39, the lower end of the screw forming a seat for the needle 37, the combination of the screw 25 and the needle constituting a needle valve adapted for closing communication between the passage 39 and the chamber 44, which is formed in the carburetor above the cup-shaped member. The pipe on which the 30 flange 42 is formed is made integral with the upper wall 7 and communicates with the laterally turned pipe 45, which is open at its end to provide an air inlet, said open end being controlled by a suitable butterfly 35 valve 46 mounted therein. Formed in the pipe 45, adjacent its open end, are openings 48 which may be closed by a sleeve 47 which is rotatably positioned on the pipe 45 in a circumferentially formed groove, the sleeve 40 47 being provided with openings which may be brought into registration with the openings 48.

Formed in the lower wall 12 is a passageway 49 which communicates with a groove 50 formed peripherally on a nut 51, which is threaded on the pipe 52 and into the casting, as at 53. The groove 50 communicates through the passageways 54 with the interior of the pipe forming portion 55, so that fuel 55 from the compartment 30 may be drawn 45 through the passageway 49 and the groove 50 and the passages 54 into the pipe 55. Openings 56 and 56' are formed in the pipe 55, so as to bring the interior of the pipe 55 into communication with the pipe 45. The diagonally extended portion which is shown in cross section and through which the pipe 55 projects is but a rib and does not form a partition so that the pipe 45 55 is normally in communication with the openings 56 and 56'. Threaded into the interior of the pipe 55 is a needle valve stem 57 having the knurled handle 58 for effecting a turning of the same, a transversely extending rib 59 being provided with an upwardly projecting boss 60 in which is threaded a screw 60' having formed in its end a seat for the end of the needle 57. By forming the seat in the end of the screw 60', 65 the screw may be threaded into the boss 60

at any desired position and the seat may be entirely removed, when desired, for replacement or repair, this operation requiring very little labor and a minimum amount of tools. Communicating with the interior of the pipe 70 55 is a laterally extending passageway 61, which communicates with a vertically extending passageway 62 adapted for communication through the passageway formed in the screw 63 with the interior 41 of the 75 pipe, which is connected to the intake manifold. An auxiliary air inlet is provided on the exteriorly threaded post 64, this inlet comprising a cup-shaped member 65 which is provided with openings 66. This cup-shaped member is provided with an interiorly projecting needle 67 adapted for closing the opening 68 upon a threading of the member 65 inwardly sufficiently. A spring 69 is positioned within the member 65 in embracing relation to the needle 67, so as to normally resist the rotating of the member 65 and thereby prevent an opening or closing, unduly, of the valve. Positioned in the interior 41 of the pipe is a sleeve adapted 80 for forming a nozzle having an interior contour of the Venturi type. Projecting upwardly from the Venturi sleeve 70 is a finger 71 adapted upon the movement of the Venturi sleeve for closing the communication between the interior 41 of the pipe and the passage 62, the finger 71 being adapted to pass beyond and cover the passageway leading from the screw 63 into the interior 41. The flow of fluid through the interior 90 41 of the pipe is controlled by a suitable butterfly valve 72. A screw 73 is provided for engagement in a groove 74 formed in the Venturi sleeve to limit the vertical movement of the Venturi sleeve. 100

In operation, when the carburetor is suitably attached to the intake manifold, the nipple 29 is connected to the fuel tank of the motor vehicle with which used. As the motor is started, a suction is created through the interior 41 of the pipe to which the intake manifold is connected. The float 34 would be so arranged and positioned because of its pivotal connection to the lug 35 as to maintain the valve in the passageway 110 open, the clip 36 assuring a withdrawal of the needle 37 upon a movement of the float 34 downwardly in response to gravity. As the suction created by the operating of the motor continues, the air or other fluid contained within the passages 40, 39 and 38 is exhausted as is also the fluid contained within the compartment 44, so as to produce a vacuum in the compartment 44. As this vacuum is produced, the base 32 of the cup-shaped member is flexed upwardly into engagement with the edge of the neck 17, thereby sealing the compartment 30 from the compartment 44. As the suction continues and the vacuum is increased, the fuel in the fuel 120 125 130

10 tank is caused to flow through the passage 26 and the passage 21 into the interior of the bore 18, which communicates by the passage 18' with compartment 44. As the fuel 5 fills the compartment 44, the float 34 rises on its pivotal connection so as to thrust the needle 37 into the seat formed in the screw 43, thereby sealing the connection between the compartment 44 and the passage 40. 15 Formed in the upper wall 7 is a small air inlet passage 7' which permits a flow of air into the compartment 44, so that, when the needle valve closes the passage 38 from communication with the passage 39, sufficient air 20 passes through the passage 7' to permit a downward movement of the base 32 to normal position, thus permitting the fuel from the compartment 44 to pass into the compartment 30. This fuel flowing through the passage 49 as the suction from the engine continues, is delivered upwardly through the passages 61 and 62 into the interior 41 and thence to the engine. This is the path of travel of the fuel when the engine is being 25 first started, and a small amount of fuel is desired, the butterfly valve 72 controlling whether or not the fuel shall pass through the passageways 61 and 62, as illustrated, or directly to the engine in a larger volume. 30 When the butterfly valve 72 is open, the fuel will be permitted to pass in a larger quantity to the engine, as will be readily understood, the fuel passing out of the pipe 55 through the openings 56 and 56'. When the 35 butterfly valve 72 is open, to permit the passage of a full supply of the fuel to the engine, it is desirous of closing entirely the flowing of fuel through the passages 61 and 62. In order to accomplish this, the Venturi sleeve is slideably arranged in the interior 41, so that the finger 71 will cover the 40 passage in the screw 63.

After the passage of the fuel from the compartment 44 into the compartment 30 45 sufficiently to allow the float to resume such a position as to again open the connection between the passage 39 and the compartment 44, the process described will be repeated, the rush of air and fuel through the 50 Venturi sleeve serving to set up the necessary suction through the passages 40 and 39. The base 12 is also provided with a groove 49' which communicates with the passageway 49, so as to assure a passage of all of 55 the fuel on the base 12 into the passage 49.

While I have illustrated and described the preferred form of structure, I do not wish to limit myself to the precise form of structure shown, but desire to avail myself of 60 such variations and modifications as come within the scope of the appended claims.

Having thus described my invention, what I claim as new and desire to secure by Letters Patent is:

65 1. A carburetor adapted for use with an

internal combustion engine having an intake manifold comprising chamber bearing means adapted for attachment to, in communication with, said manifold; a flexible dividing member adapted for dividing said carburetor 70 into a pair of compartments, said compartments being normally in communication with each other and said flexible member being adapted for sealing said compartments from communication with each other upon 75 the flexing of said member beyond a predetermined point in one direction; fluid conducting means communicating with one of said compartments and adapted for delivering fluid thereto; a float mounted in said compartment last mentioned; means operable by said float for closing communication of said compartment with said manifold upon the delivery of a predetermined amount of fluid into said compartment. 85

2. A carburetor adapted for use with an internal combustion engine having an intake manifold comprising chamber bearing means adapted for attachment to, in communication with, said manifold; a flexible member 90 mounted in said carburetor and adapted for dividing the same into a pair of compartments, said compartments being normally in communication with each other and said flexible member being adapted for sealing said compartments from each other upon a flexing of said member in one direction beyond a predetermined point, one of said compartments being in communication with said manifold for permitting the rarefying 95 of gases contained in said compartment upon the operating of said engine, said flexible member being adapted for flexing beyond said predetermined point upon the rarefying 100 of said gases; fluid conducting means communicating with said manifold communicating compartment; means mounted in said compartment for closing communication of said compartment with said manifold upon the delivery into said compartment of a predetermined amount of fluid, said compartment having an air duct communicating thereto for permitting the flexing of said flexible member to normal position upon the closing of said communication of said compartment with said manifold. 110

3. A carburetor adapted for use with an internal combustion engine having an intake manifold comprising chamber bearing means adapted for attachment to, in communication with, said manifold; a bottom wall; a top wall; a side wall forming member adapted for engagement at its opposite ends with said top and bottom walls for forming a chamber; a cup-shaped member adapted for mounting in said chamber and having its open end angularly turned for engagement between said bottom and said wall forming member, the base of said cup-shaped member being flexible and adapted for dividing said 125 130

chamber into a pair of compartments normally in communication with each other, said base being adapted for sealing said compartments from communication with each other upon flexing in one direction beyond a predetermined point, one of said compartments being normally in communication with

said manifold; and means in said compartment for closing said communication automatically.

10

In testimony whereof, I have signed the foregoing specification.

HALSEY C. ABERN.
